(57) **CLAIM**

The ornamental design for an electrode housing and indicator, as shown and described.

DESCRIPTION

FIG. 1 is a top view of the new design for an electrode housing and indicator;

FIG. 2 is a bottom view of the new design for an electrode housing and indicator;

FIG. 3 is a front view of the new design for an electrode housing and indicator, the back of the electrode housing and indicator being a mirror image of FIG. 3;

FIG. 4 is a right side view of the new design for an electrode housing and indicator;

FIG. 5 is a left side view of the new design for an electrode housing and indicator;

FIG. 6 is a bottom perspective view of the new design for an electrode housing and indicator; and,

FIG. 7 is a top perspective view of the new design for an electrode housing and indicator.
